UNITED STATES PATENT OFFICE.

ALBERT B. BERNHARD, OF COLUMBUS, OHIO.

INTERNAL-COMBUSTION ENGINE.

Application filed July 27, 1921. Serial No. 487,975.

To all whom it may concern:

Be it known that I, ALBERT B. BERNHARD, a citizen of the United States, residing at Columbus, in the county of Franklin and

5 State of Ohio, have invented certain new and useful Improvements in Internal-Combustion Engines, of which the following is a specification.

This invention relates to improvements in 10 internal combustion engines, and has for its primary object to provide an engine of the two cycle variety wherein improved features of design and construction are present for the purpose of effecting a positive intro-

15 duction of the fuel charge into the cylinders of the engine and to effect this result in such manner that a thorough scavenging of burnt gases from the cylinders will be positively brought about.

20 Another object of the invention resides in the provision of an internal combustion engine of two cycle construction wherein a pair of longitudinally aligned cylinders is provided, the said cylinders being 25 equipped with pistons rigidly connected for movement in unison by a slideable rod structure, the said pistons moving in opposition to each other in their respective cylinders so that the firing stroke of one piston will 30 produce a compression stroke on the part of the other companion piston and vice versa.

A further object of the invention rests 35 in providing an annular charge receiving compartment intermediate of the said cylinders, the said compartment being adapted to receive a slideable charge controlling piston capable of being positively operated, at predetermined intervals, from the crank 40 shaft to the engine, and to provide cooperative inlet and exhaust valves in conjunction with the compartment, said valves being responsive to the operation of the piston to admit the fuel mixture into the said compartment and to discharge the same into 45 the firing cylinders of the engine at proper predetermined periods of operation.

Other objects of the invention reside in 50 the provision of a two cycle engine of simple, efficient and compact construction capable of developing unusual power and yet to be light in weight and small and compact in design; in providing automatically operating fuel inlet and outlet valves for the charge receiving chamber; in the provision of improved means for governing the opera-

tion of the piston in the charge receiving chamber and in various other details of design and operation to be hereinafter more particularly set forth.

60 From the accompanying drawings, forming a part of this specification, and in which similar characters of reference denote like and corresponding parts throughout the several views thereof:

65 Figure 1 is a longitudinal sectional view taken through an engine constructed in accordance with the principles of the invention, parts thereof being shown in side elevation.

70 Figure 2 is a vertical transverse sectional view taken on the plane disclosed by the line 2-2 of Figure 1.

75 Figure 3 is a plan view of the engine.

Figure 4 is a vertical sectional view taken on the line 4-4 of Figure 3 and disclosing more particularly the discharge valve structure for the fuel chamber.

Figure 5 is a horizontal sectional view 80 taken through the fuel chamber on the line 5-5 of Figure 2.

Figure 6 is a detail sectional view disclosing the cam structure for effecting the operation of the piston and the fuel chamber.

85 Referring more particularly to the drawings, the numeral 1 designates the engine comprising the present invention in its entirety. The engine consists generally of a crank case 2 and superposed longitudinally spaced vertically extending cylinder structures 3. The crank case is formed to include intermediate and outer longitudinally aligned bearings 4, in which is rotatably journaled a suitably balanced crank shaft 90 5, the said shaft having its cranks provided with balance weights 6 of usual construction, and a fly wheel 7 is rotatably connected with the shaft and confined for rotation between the intermediate bearings 4, the 95 said crank shaft projects beyond the confines of the crank case in order that its power may be transferred for the driving of any suitable machinery or apparatus in the ordinary manner common to power 100 plants of this character.

105 The cylinder structures each consist of a pair of working cylinders 8 and 9, which are situated in vertical alignment and are formed in water jacketed cylinder blocks 10. 110 These cylinders slidably receive the working pistons 11, which are united by means of a

- rigid slidably disposed rod 12, the latter causing the pistons to move in opposition to each other in their respective cylinders 8 and 9, that is, when the piston in the cylinder 8 is moving downwardly to effect its compression stroke, the piston in the lower cylinder 9 will be moving downwardly on its firing stroke, the connection between the ends of the rod 12 and the pistons 11 permitting 5 of this feature of operation. It will be understood that the upper end of the cylinder 8 and the lower end of the cylinder 9 are left open to permit of proper operation without undue fluid compression, on the part of the 10 pistons. The block 10 is formed to include a vertical centrally disposed bearing 13 between the cylinders 8 and 9 which is adapted to slidably receive and to properly position the rod 12.
- 15 As shown, between the cylinders 8 and 9 and disposed concentrically and around thereof, the block 10 is enlarged as at 14 to produce an angular fuel receiving chamber 15, wherein is slidably mounted a hollow 20 ring like piston 16, which through suitable mechanism is adapted to be vertically reciprocated within the confines of the chamber 15. As shown, the perimeter of the piston 16 is formed to include packing rings 17, 25 and the inner wall of the chamber 15 is suitably grooved to receive cooperative packing rings 18, the said rings 17 and 18 operating in conjunction with the piston 16 and the walls of the chamber 15 to prevent un- 30 due fluid passage through or around the piston 16 during its operation. Communicating with the chamber 15 are fuel inlet connections 19 for each of the cylinders 8 and 9, one set of the fuel connections being located 35 at the upper part of the chamber 15 and the other set at the lower part of said chamber, there preferably being two of such connections for each cylinder. It will be understood that the connections 19 may be connected 40 with a common source of fuel supply, not shown, such for example as the engine carburetor.
- 45 Between the connections 19 and the chamber 15, the cylinder block 10 is provided with 50 replaceable valve seats 20, which are adapted to receive inwardly opening valves 21, the said valves having their vertically disposed stems 22 slidably positioned within fixed bearing sleeves 23, and springs 24 are 55 positioned between the ends of the sleeves 23 and enlargements 25 on the ends of the stems 22, the said spring 24 serving thereby to normally maintain the valves 21 in engagement with the seats 20. However, it 60 will be apparent that when the piston 16 moves away from the valves 21, a partial vacuum will be created within the chamber 15 which will serve to enable the valves 21 to open, against the resistance offered by 65 their springs 24, under atmospheric pres-

sure. When thus opened, the fuel will be admitted into one side or the other of the chamber 15, and when the pressure on the opposite sides of the valve 21 becomes balanced, the said valves will automatically close 70 to retain the fuel charge drawn thereby within the chamber 15, from which it is delivered in a controlled manner to the cylinders 8 and 9.

This cylinder block is enlarged, contiguous 75 to the walls of the chamber 15, to provide ducts 26 by means of which a fuel charge may be led from the chamber 15 to the heads of the cylinders 8 and 9. These ducts are normally closed, however, by means of automatically operated discharge valves 27, 80 which are arranged to engage the valve seats 28 surrounding ports formed in the walls of the chamber 15, the said valves 27 by engaging with the seats 28 normally close said 85 port so that fluid communication between the chamber 15 and the ducts 26 is normally closed. The valves 27 are provided with stems 29 which are arranged to be received within removable plugs 30 suitable secured 90 in the enlargements of the cylinder casing 10. The plugs 30 are provided with casings 31, wherein are housed springs 32, which surround the outer ends of the stems 29 and cooperate therewith, as shown, to maintain 95 the said valves in their seated positions. By this construction it will be apparent that upon movement of the piston 16 toward the outwardly opening valves 27, fluid pressure 100 will be exercised upon said valves so as to cause the latter to uncover their respective ports, thus enabling the piston to forcibly operate to cause a positive flow of the fuel charge therein into the duct 26, and then 105 into the cylinders 8 and 9.

It will be understood that the fuel charge delivered to the cylinders 8 and 9 will be subjected to the usual action of the pistons 11, that is, when the fuel is drawn into the working cylinders, one piston will advance to compress the charge, while the other will be moving outwardly on its firing stroke. The cylinders 8 and 9 are provided with exhaust ports 33 which are situated in such relation with respect to the pistons 11 that when the latter have been moved outwardly to the extreme limit afforded by their expansion strokes, the ports 33 will be uncovered to permit of the exhaust or escape of the consumed or burnt fuel charge. A thorough 115 scavenging of the cylinders is secured by reason of the fact that when the pistons move on their expansion strokes, high pressures will be created in the heads of the working cylinders which will act upon the valves 27 to maintain the latter in their seated positions, however, when the pistons reach a position initially beginning to uncover the exhaust ports 33, the piston 16 will be suddenly reciprocated by positive means to open 120 125 130

the valve 27 to admit a fresh fuel charge, the opening of the valve 27 being facilitated by the fact that the internal pressures within the cylinders has been diminished by the 5 partial uncovering of the exhaust ports. It will be apparent that the forcible inrushing of the fresh fuel charge will cause the burnt gases to be forcibly ejected from the exhaust ports before the latter are again covered by 10 the inward movement of the pistons on their compression strokes. Since the piston 16 is quickly operated to force a fuel charge into the working cylinders, it follows that its operation will also be equally effective and 15 prompt in the opening of the inlet valve 21, a feature which insures a quick inrush of the fuel charge into the chamber 15, thus insuring a proper intake of the fuel with each operation of the piston. The heads of the 20 cylinders may be provided with suitable spark plugs 34, capable of producing the necessary spark to explode the charge when the said pistons 11 reach the limits of their compression strokes.

25 To effect the positive operation of the piston 16 for each cylinder block the crank shaft is provided with a cam 35, which is adapted for cooperation with rollers 36 carried by a U shaped yoke 37. This yoke is pivoted as 30 at 38, in order that the rotation of the cam 35, in unison with the crank shaft 5 will result in oscillating the yoke 37 at predetermined periods. The cam is of triangular configuration, and its construction and timing is such that the piston 16 will be quickly raised and lowered in an intermittent manner and maintained in repose at its extremity of movement within the chamber 15. The upper leg of the yoke 37 is pivotally 35 connected as at 39 with the lower bifurcated end of a connecting link 40, the upper end of said link being connected with a cross pin 41, located in the sleeve 42 integrally formed with and projecting downwardly from the piston 16, the said sleeve being located within suitable bearings 43 provided in conjunction with the casing 10, and the bearings 43 are provided with slots 44 capable of receiving the ends of the pin 41 and of sufficient 40 length to permit of the rise and fall of the piston 16, the said sleeve 42 being provided with piston rings 45 for the purpose of assisting in maintaining compression within the chamber 15. The connecting link 40 45 may be suitably encased by means of a casting 46, carried by the upper part of the crank case 2. In this construction it will be apparent that positive means are provided for effecting the movement of the piston 16, and that by such construction the said piston 16 will operate intermittently and at proper intervals to draw the mixture into the chamber 15 and to forcibly expel the same from said chamber into the cylinder heads 8 and 9. 50 It will be understood that the lowermost 55 of the pistons 11 are united by means of the usual connecting rods 47 with the crank shaft 5, so that the power developed within the working cylinders may be transferred in the customary manner to the crank shaft. 70 Also, it will be appreciated that the cylinder casings 10 may be suitably jacketed to permit of a sufficient water circulation, for the purpose of maintaining the engine at proper working temperatures. The lubricating system may be one of many kinds, however, it is proposed that a lubricant shall be drawn into the cylinder structures with the fuel charge, as this system permits of the lubrication of the pistons 11 and 16, and other 75 cooperative movable parts, such for example as the valve stems. The ordinary splash system may be used for lubricating the movable parts found in the crank case 2.

From the foregoing description, taken in 80 conjunction with the accompanying drawing, it will be apparent that the present invention provides an internal combustion engine of relatively simple, compact and durable design, wherein an improved arrangement of the working cylinders is provided and also a very effective mechanism for introducing the fuel charge into the cylinders of the engine and in exhausting the consumed fuel. It is by reason of this construction that the present invention is enabled to employ the two cycle principle of operation. That is, by the provision of the piston 16 85 and the two sets of inlet and exhaust valves for each cylinder, a fuel charge of proper 90 volume may be admitted into the working cylinders to secure efficient results and to insure a complete discharge of the consumed fuel from the cylinders 8 and 9 by way of the double exhaust ports 33. It will be understood that the specific construction of the engine disclosed may not be strictly adhered to in carrying out the invention, but that changes in the relative area of the various parts or chambers of the engine may be 95 made or other similar alterations without departing from the spirit of the invention.

100 What is claimed is:

1. A two cycle internal combustion engine comprising a cylinder structure including a 105 pair of working cylinders and an intermediate disposed fuel receiving chamber, pistons mounted for reciprocation within said cylinders, a crank shaft, connections between said pistons and crank shaft, a fuel 110 controlling piston mounted in said chamber, automatically operating valve mechanism cooperative with said chamber and operated by said piston within the chamber for delivering fuel to said cylinders, and a positive operating connection driven from said crank shaft for effecting the operation of the piston within said chamber when said pistons occupy predetermined positions in 115 their respective cylinders.

2. A two cycle internal combustion engine comprising a cylinder structure including a pair of longitudinally aligned working cylinders and an intermediately disposed fuel receiving chamber, pistons mounted for joint reciprocation within said cylinders, a crank shaft, a connection between one of said pistons and said crank shaft, a fuel controlling piston mounted in said chamber, automatically operating valve mechanism cooperative with said chamber and operated by said piston within the chamber for delivering fuel to said cylinders, and a positive operating connection driven from said crank shaft for effecting the operation of the piston within said chamber when said piston occupies predetermined positions in their respective cylinders.
3. A two cycle internal combustion engine comprising a cylinder structure formed to include a pair of vertically aligned working cylinders, and an intermediately located concentrically disposed fuel receiving chamber, a piston slidably mounted within said chamber, automatically operating inlet valves disposed in communication with said chamber and on opposite sides of said piston, ducts leading from said chamber to said cylinders, valves controlled by the movement of said piston for admitting of the passage of fuel from said chamber to said cylinders, opposed pistons mounted for reciprocation within said cylinders, a crank shaft, a connecting link between said crank shaft and one of said opposed pistons, and a positive operating connection operated by said crank shaft for reciprocating said valve controlling piston when either of said opposed pistons assumes a position substantially uncovering the exhaust ports of said cylinders.
4. In a two cycle internal combustion engine, a cylinder structure including a pair of vertically aligned working cylinders, and a concentrically situated fuel receiving chamber disposed between said cylinders, a piston disposed for reciprocation within said chamber, automatically operating inlet and exhaust valves communicating with said chamber and disposed on opposite sides of said piston and whereby upon the operation of the latter, fuel will be drawn into said chamber and thence into said cylinders, a crank shaft, a connecting link between said shaft and one of said pistons, a cam carried by said crank shaft, an arcuate rocker arm cooperative with said cam for engagement therewith at predetermined intervals, and a rod uniting said rocker arm with said valve operating piston.

In testimony whereof I affix my signature.

ALBERT B. BERNHARD.
